Dec. 1459

Elemir J. Key, of Lowell, Mass.
Assignor to the
Lowell Manufacturing Company.
Letters Patent No. 94 dated Aug. 13. 1861.
Whole No. 1459.

The schedule referred to in these Letters Patent and making part of the same.

To all whom it may concern.

Be it known, that I, Elemir J. Key, of Lowell, in the County of Middlesex, and State of Massachusetts, have originated and designed a new Pattern for carpets or other fabrics, of which the following is a full, clear and exact description, reference being had to the accompanying drawings, making part of this specification.

Fig. A is a group of fruit and leaves, resting on a plain ground.

Figs. 1 and 2, when matched form a group similar to Fig. A.

Fig. B is a broad band with serpentine borders, and a large vine of leaves and flowers running through the centre.

Fig. C is another broad band with serpentine borders, and an anterior of mottled work. This band runs under, and at right angles with, the band B. When the design is matched, the sections 3 and 4, form continuations of the bands B and C.

The colors employed for the different portions of the design may be varied to suit the taste and the wish of the manufacturer.

Claim.

What I claim as my invention and desire to secure by Letters Patent, is the design or pattern, for carpets or other fabrics, herein set forth.
